United States Patent Office

Des. 230,417
Patented Feb. 19, 1974

230,417

ENDLESS TRACK

Guy-Noel Chaumont, Tring-Junction, Quebec, Canada,
assignor to Dayco Corporation

Filed May 12, 1972, Ser. No. 252,961

Term of patent 14 years

Int. Cl. D15—04

U.S. Cl. D40—5

FIG.1

FIG.2

FIG. 1 is a perspective view of an endless track showing my new design, it being understood that the tread design continues uniformly through the belt indicated in light, full lines; and

FIG. 2 is a top plan view of the section of the tread design shown in FIG. 1.

I claim:

The ornamental design for an endless track, as shown and described.
